Inventor:

Charles Henry Quimby, Jr.

UNITED STATES PATENT OFFICE.

CHARLES HENRY QUIMBY, JR., OF MOUNT VERNON, NEW YORK.

METAL SHEET-PILEING.

1,183,403.

Specification of Letters Patent. Patented May 16, 1913.

Application filed April 7, 1914. Serial No. 830,187.

To all whom it may concern:

Be it known that I, CHARLES HENRY QUIMBY, Jr., a citizen of the United States, and a resident of Mount Vernon, in the county of Westchester and State of New York, have invented certain new and useful Improvements in Metal Sheet-Piling, of which the following is a specification.

My invention relates more particularly to steel sheet piling of the kind which is built up of separate piles or sections, provided with interlocking flanges along both edges, whereby the pile as driven, interlocks with the adjoining pile and forms a continuous wall or sheet of piling. Such piling is now generally used for coffer-dams, retaining walls, core-walls of dams, sheeting of excavations and for numerous other purposes.

The object of the invention is to provide a novel metallic sheet piling having novel interlocking edges, the construction of which permits the piling to be assembled in various forms without using special constructed pieces.

Another object of this invention is to provide a metallic sheet piling of such construction that the independent piles or sections will have their metal so distributed as to give them the greatest strength for the amount of material used, both as to stiffness and longitudinal resistance to failure in the interlock.

With the above and other objects in view, the invention consists in the novel construction, combination and arrangement of parts to be hereinafter more fully described, and specifically pointed out in the claims.

In describing the invention in detail reference is had to the accompanying drawings, forming a part of this application and wherein like letters of reference indicate like parts throughout the several views, in which—

Figure 1 is a top plan view of one form of my improved metal sheet piling, showing one pile or section complete, engaging the adjoining pile of like form or cross-section, Fig. 2 illustrates a top plan view showing a full pile section of a modified form in which the web is curved, Fig. 3 illustrates a top plan view showing a modified form of a full pile section in which the web

lies on or near the center line of sheeting when assembled, Fig. 4 illustrates a top plan view showing a full pile section of a modified form, and Fig. 5 illustrates a top plan view showing a full pile section of a modified form in which the flanges are bent out of the plane of the web to the side opposite to that shown in Fig. 1.

By reference to the drawing, it will be seen that Fig. 1 illustrates a form of piling in which *a* is the web; *cc* is the compound hook and guard flange; *bd* the T flange; and *f* an inclosure or groove formed by the hook flange and the near leg of the T flange. The groove is of such size and form as to conveniently receive the T flange of an adjoining pile. The outer arm *c* of the hook flange and the legs of the T flange *b* lie in approximately the same plane, at an angle to the line of sheeting, and at a distance apart sufficient to allow the stem *d* of the T flange of the adjoining pile to pass between freely. By this arrangement of the flanges, a complete triple hook interlock is secured, when the piling is assembled to form a continuous line or sheet, namely, *c* to *b'*, *b'* to *b* and *b* to *c'*; and a double hook and guard interlock is secured when the piling is assembled to form an angle, namely, *b* to *b''*, *b''* to *c* and *c''* to act as the guard. The hook flange *c*, groove *f* and legs of the T flange *b*, face at an angle *X* to the line of sheeting. Two adjoining piles when assembled in a reverse formation or interlock, as piles *a* and *a''*, form an angle *Y*. This angle *Y* is always equal to double the angle *X*. Should the angle *X* equal 45 degrees, the angle *Y* would equal 90 degrees and a rectangular formation or interlock of the sheeting could be secured. Should the angle *X* equal 22½ degrees, the angle *Y* would equal 45 degrees and the line of sheeting could be continued on that angle or another angle of 45 degrees added and the rectangular formation secured with the use of one corner pile only, set at 45 degrees. From this it will be seen that the piles may be assembled in such lines and angles as will best suit the conditions.

The novel features of the invention are principally the following: The manner of arranging the flanges of the interlock so as

- to secure a complete triple hook engagement when assembled in a continuous sheet, and a double hook and guard engagement when assembled in the reverse position to form an angle; the placing of the terminal portions of the hooks of a triple hook interlock, in the same plane, so as to allow them to be assembled in an alined or angular formation; and the arrangement of the flanges in a 5 angle; the placing of the terminal portions of the hooks of a triple hook interlock, in the same plane, so as to allow them to be assembled in an alined or angular formation; and the arrangement of the flanges in a 10 complete triple hook interlocking sheet pile, in such a manner as to allow the rolling of the piles in their manufacture, to be done with a comparatively little bending of the metal in the final pass.
- 15 The function of the curved guard flange of the present types of piling, is only that of retaining the hook flanges of the like adjoining piles in their engagement one with the other, while the complete triple hook 20 flange form has a compound hook flange opposite the double or T flange which serves a double purpose, namely, that of retaining the T flanges of the adjoining piles in engagement as a guard, and that of hooking 25 about the outer leg or hook of the T flange of the adjoining pile, to resist its tendency to rotate under strain. The failure of the interlock due to longitudinal strain in the sheet of piles is manifested generally by a 30 spreading or bending out of the hook flanges. With the present forms there is a single hook and guard, or a double hook arrangement of the flanges, but with this complete triple hook interlock, three complete 35 hooks are used.

It is evident that the three hooks of the triple hook interlock when under maximum load, act as a lever, since the stress is taken up by the three hooks and balanced before 40 failure. Under this condition, the legs of the T flanges act as the lever arms, the stress on the single hooks being applied at the long end of the lever arms, the fulcrum being at the point of contact of the inner legs of the 45 T flanges, and the loads applied through the stems of the T flanges. As the lever arms are about double the length of the load arms, the load on the stem of the T flanges could be approximately double the stress on the 50 hook flanges, or the stress on the hook flange one-third the total load transmitted from the web. It must be noted however, that these conditions are only reached at the 55 point of failure, as at other times the stress on the single hook flange is less than one-third the total load transmitted from the web. It is for this reason that the complete triple hook form described gives an increased strength of the interlock over the 60 present forms, of 50% to 100%, for equal weight of piles or sections.

In the device, I have provided a groove f which allows sufficient room for the T flange or the inclosed flange of the adjoining pile

to move freely and permit of the piles following a curved line. The curved line along which a sheet of piling may follow, is limited however, to a few degrees of angle between the adjoining piles, the greater angles being provided for by reversing the 65 piles in the interlock. The extra space in the groove may also be used, if desired, to permit strips of wood or other material to be inserted as packing, to add to the watertightness of the interlock. This however, 70 is not very often necessary as the contacts of the flanges are generally sufficiently tight to prevent any considerable amount of leakage.

The piles or sections will be manufactured 80 from steel or other suitable material, the best plan being to use steel and roll them in integral sections. These piling forms can be economically rolled.

Several modified forms have been illustrated, any two of which may be interlocked together, but it will be understood however, that other forms of slight variations from these, may be resorted to without departing 85 from the spirit of my invention.

What I claim as new and desire to secure by Letters Patent is:—

1. A metal sheet pile comprising a web portion having flanged vertical edges, each of the said edges consisting of one member curved out of the plane of the web and terminating in two free edges bent back on either side, and another member curved out of the plane of the web and its outer portion bent back toward the other member, the 95 same being adapted to interlock with a like adjoining pile in a direct position to be alined or in a reverse position to set at an angle.

2. A metal sheet pile comprising a web 105, portion having flanged vertical edges, each of the said edges consisting of one member curved out of the plane of the web and terminating in two free edges bent back on either side and another member curved out 110 of the plane of the web and its outer portion bent back toward the other member, the same being adapted to interlock with a like adjoining pile, as a triple hook engagement in the direct position, and as a double hook 115 and guard engagement in the reverse position.

3. A metal sheet piling interlock comprising in combination, a T shape flange, a hook shape flange and a groove, the free edges of 120 the said T flange and edge of the said hook flange to lie in the same plane, the said groove to be formed by the said hook flange and near edge of the said T flange, the said groove adapted to receive a like T flange and 125 the outer edge of the T flange adapted to engage a like hook flange of a like adjoining combination in an alined formation, and

the said groove adapted to receive a like T flange of a like adjoining combination when reversed to form an angle, in which engagement the said hook flange falls within the 5 groove of and is guarded by the hook flange of the adjoining like combination.

Signed at Mount Vernon in the county of

Westchester and State of New York this 2nd day of April A. D. 1914.
